TION OF CALIFORNIA

AIR-SUPPLYING MEANS FOR CLOSED-TOP GAS-STOVE BURNERS

Application filed August 28, 1924. Serial No. 734,631.

Our invention relates to a device for supplying air to cooking-top burners such as are arranged in a compartment provided with a closed top.

5 Most gas stoves, and particularly ranges, are supplied with front and rear sets of top gas burners. Where a grate has been superposed over the burners to provide a cooking top, no difficulty has been experienced in the 10 matter of the adequate supply of air for the different burners. However, when the burners are superposed by a closed or solid top, it has frequently been found that the rear burners receive less air for combustion than 15 do the front burners, since the burner compartment is usually open only at the front and is desirably shallow. In accordance with the latter difficulty, it is an object of our invention to provide means for insuring an 20 adequate supply of fresh air to the burners and thus insure proper combustion of the fuel.

Another object of the invention is to provide means for supplying air to the rear burners which will not require the use of a deformed or undersized drip pan under the burners.

The invention possesses other objects and features of advantage, some of which, with 30 the foregoing, will be set forth in the following description of the preferred form of our invention which is illustrated in the drawings accompanying and forming part of the specification. It is to be understood 35 that we do not limit ourselves to the showing made by the said drawings and description, as we may adopt variations of the preferred form within the scope of our invention as set forth in the claims.

40 Referring to said drawings:

Figure 1 is a vertical sectional view of a fragment of a gas stove showing a rear top burner equipped with the device of our invention.

45 Figure 2 is a plan view of the burner and device shown in Figure 1.

Figure 3 is a plan view of the cooking top.

As illustrated in the drawings, the device of our invention is embodied in a stove 4 provided with a closed or solid gas cooking-top

6. The latter comprises a top gas-burner compartment 7 whose sides are defined by side walls 8 and 9 and a rear wall 12. The bottom of the compartment is preferably defined by a plate 13, while the top is closed by a cooking plate 14, here shown provided with openings 16 normally closed by means of lids 17. The compartment 7 is desirably shallow so that a maximum space may be available below the compartment for other uses.

Arranged in the compartment 7 are front and rear gas burners 18 and 19 respectively, here shown supported by means of cross rods 21 and aligned with the lid openings 16. The proper gas mixture for the burners is arranged to be supplied thereto through pipes 22 connected to the gas manifold 23 at the front of the stove. Air for completing combustion is arranged to enter the compartment through the opening 24 at the front thereof, and the products of combustion are arranged to discharge through a vent 26 located at the rear of the compartment and with at least a portion thereof in a higher plane than is the top of the opening 24. It will thus be noted that a draft is set up from the front to the rear of the compartment. Since the indrawn air crosses the front burners first, the major portion of the oxygen therein is taken therefrom to complete the combustion process at these burners, with the result that the air which reaches the rear burners seldom provides sufficient oxygen for such burners.

Primarily in consequence of the foregoing, means are provided for insuring an adequate supply of oxygen to the rear burners. In the present embodiment of the invention, such supply is arranged to be taken directly from a source extraneous to the burner compartment. Arranged within the compartment and, as here shown, spaced from the bottom plate is a conduit 27 through which air from behind the stove is adapted to be drawn and guided to the flame of a rear burner, one of said conduits being preferably provided for each of said burners. The intake end 28 of the conduit extends through an opening 29 provided in the rear wall 12 of the compartment, while the outlet end 31 of the conduit

is enlarged and is adapted for the reception of the burner, clearance between the burner and walls of the conduit end 31 being provided so that the air may readily circulate around 5 all portions of the burner to thus provide desired distribution of the air. The top edge 32 of the conduit is preferably above the top of the burner, so that the products of combustion travelling from the front burners to 10 the vent will not interfere with the supplying of air to the flame from the conduit. If desired, the portion of the conduit surrounding the burner may be shaped to approximately conform to the arrangement of the 15 burner jets and thus promote the more uniform distribution of air to them. To still further enhance the desired air flow, the conduit is so designed that its effective area of discharge exceeds the area of the intake. In 20 this manner, expansion of the air, due to the heating thereof as it passes through the conduit, will not create back pressure and thereby retard the flow of air to the burners.

Each conduit is here shown arranged to be 25 supported in the compartment by the cross rod 21. In the present embodiment of the invention the conduit is formed in upper and lower separable sections 33 and 34 respectively. The lower section is preferably provided 30 with hook portions 36 by means of which it may be removably hung on the rod 21, while a flange 37 is provided adjacent the intake end by which it may be releasably held supported in the wall. The upper section 33 of 35 the conduit is here shown arranged to be supported by the lower section 34 thereof, the forming of the conduit in separable sections being designed to allow the removal and replacement of the conduits and burners without necessitating removal of the cross rod 21.

It will be noted that with the conduits formed and applied as shown, the bottom of the burner compartment is not effected by the 40 operation of the device, with the result that the drip pan 38 which is usually placed under the burners, need not be of special construction. If desired, a drip opening 39 may be provided in the bottom of the conduit to allow 45 drainage.

We claim:—

1. In combination with the burner chamber of the cooking top of a closed-top gas stove, a burner mounted in said chamber, a supporting member for said burner, air supplying 50 means for said burner comprising a conduit formed in vertically separable sections and arranged to supply air to said burner from a source external to said chamber, the lower section of said conduit being arranged to be supported by the burner supporting member, and the upper section of said conduit being arranged to be supported by said lower conduit section.

2. The combination with a stove having a 55 cooking top and a plate spaced below said

top to define with the top a chamber, a burner supported between the top and plate free from contact therewith, a pipe leading from the front of the stove between and independent of the top and plate for supplying fuel to 60 said burner, a member surrounding said burner in circumferentially spaced relation thereto with its upper and lower ends, open and disposed above and below the burner, said member having a notch therein through 65 which said pipe extends to the burner, and a conduit leading from the back of the stove to the lower end of said member and supplying atmospheric air thereto, said conduit being 70 independent of and spaced between said top and plate.

In testimony whereof, we have hereunto set our hands at Oakland, California.
